UNITED STATES PATENT OFFICE.

ROBERT H. HARRIS, OF ALBANY, OREGON.

CHIROPRACTIC TABLE.

Application filed November 3, 1923. Serial No. 672,563.

To all whom it may concern:

Be it known that I, ROBERT H. HARRIS, a citizen of the United States, residing at Albany, in the county of Linn and State of Oregon, have invented certain new and useful Improvements in Chiropractic Tables, of which the following is a specification, reference being had to the accompanying drawings.

10 This invention relates to certain improvements in chiropractic tables and it is an object of the invention to provide a novel and improved device of this general character which may be readily folded or compacted, when not in use, to occupy a minimum of space so that the same may be readily and conveniently transported whereby the treatments may be given at the home or other places aside from the office.

15 It is also an object of the invention to provide a novel and improved device of this general character which may be readily and conveniently adjusted for use in connection with a bed or the like and in a manner without the necessity of the patient at any time being entirely out of bed.

20 Furthermore it is an object of the invention to provide a novel and improved device of this general character which may be adjusted or folded in a manner to permit the same to be used with the patient in a kneeling position in accordance with "the new posture" method now being extensively employed by chiropractors.

25 It is also an object of the invention to provide a device of this character embodying an abdominal pad together with novel and improved means whereby said pad is effectively supported in a manner to properly resist the thrust imposed upon the patient during treatment, said supporting means being resilient and having associated therewith means for regulating the tension thereof.

30 Another object of the invention is to provide a novel and improved device of this general character constructed in a manner whereby is eliminated the slipping or tilting of the table when properly placed or adjusted into desired position.

35 The invention consists in the details of construction and in the combination and ar-

angement of the several parts of my improved chiropractic table whereby certain important advantages are attained and the device rendered simpler, less expensive and otherwise more convenient and advantageous for use, as will be hereinafter more fully set forth.

40 The novel features of my invention will hereinafter be definitely claimed.

45 In order that my invention may be the better understood, I will now proceed to describe the same with reference to the accompanying drawings, wherein:—

50 Figure 1 is a view in top plan illustrating a table constructed in accordance with an embodiment of my invention and in extended or working position;

55 Figure 2 is an enlarged view in bottom plan of the table as herein disclosed;

60 Figure 3 is a longitudinal sectional view taken through the device as herein disclosed and adjusted for use in connection with a bed or the like;

65 Figure 4 is a view in side elevation illustrating the device as herein disclosed adjusted for position to be used in connection with a patient kneeling and in accordance with "the new posture" method, a second position of certain of the features being indicated by broken lines;

70 Figure 5 is an enlarged fragmentary view partly in elevation and partly in section illustrating an adjustable leg as herein employed;

75 Figure 6 is a view in end elevation of the structure as particularly illustrated in Figures 1 and 2;

80 Figure 7 is a view in perspective of one of the bars for supporting the abdominal pad;

85 Figure 8 is a view in perspective of one of the bars for supporting the chest pad;

90 Figure 9 is an end elevational view of the device as illustrated in Figures 1 and 2 and opposite to that illustrated in Figure 7;

95 Figure 10 is a view in perspective of one of supporting feet as herein comprised;

100 Figure 11 is a view in perspective of a leg section with which directly coats a foot such as illustrated in Figure 10;

105 Figure 12 is a view in perspective of the frame to provide an additional support for

the abdominal pad and which coacts with supporting bars such as the one illustrated in Figure 8;

Figure 13 is an elevational view illustrating the device folded or compacted for transportation;

Figure 14 is a fragmentary view partly in section and partly in elevation illustrating one of the supporting feet in another position;

Figure 15 is a sectional view taken substantially on the line 15—15 of Figure 14;

Figure 16 is a view in perspective of the adjustable stop disclosed in Figures 14 and 15;

Figure 17 is a fragmentary view in bottom plan illustrating a further embodiment of my invention;

Figure 18 is a view partly in section and partly in elevation of the structure as illustrated in Figure 17;

Figure 19 is a view in perspective, unapplied of one of the supporting bars for the head pads;

Figure 20 is a view partly in section and partly in elevation illustrating a hand grasp in engagement with an angle bar.

As disclosed in the accompanying drawings, H denotes the head supporting pads, B the chest supporting pad and A the abdominal supporting pad. Each of these pads comprises a base board 1 having arranged thereon suitable upholstering 2 which may be of any preferred material.

The head pads H have secured to the base boards 1 thereof the angle bars 3 extending longitudinally of said pads and said bars 3 at predetermined points spaced longitudinally thereof are connected by the cross strips 4 whereby the pads H are maintained in desired spaced relation. The inner ends of the bars 3 have their depending flanges extended, as at 5, and which extended portions 5 are freely engaged with a cross member 6 herein disclosed as cylindrical in form. The opposite end portion of the member 6 has secured thereto the legs 7 preferably disposed in downward divergence one with respect to the other. The legs 7 are preferably tubular so as to have telescopically engaged therewith an extensible or adjustable leg 8 provided at its outer end with a pad or foot 9 of rubber or kindred material. The leg 8 is held or locked into desired adjustment with respect to its associated leg 7 through the medium of the clamping screw 10 threaded through a wall of the leg 7 and having requisite contact with the inserted end portion of the leg 8.

Each of the bars 3 and an adjacent leg 7 have associated therewith a bracing member M comprising a pair of pivotally connected rigid members 11 and 12, the outer end portion of the member 11 being pivotally connected, as at 14, to the bar 3 while the outer

end portion of the member 12 is pivotally connected, as at 15, with the collar 16 or the like suitably positioned upon the leg 7. The pivoted end portion of the member 11 is provided with an extension 17 which overlies the adjacent end portion of the member 12 when the brace is in extended or working position, and said extended portion 17 is provided with a laterally disposed lug 18 to engage the adjacent portion of the member 12 whereby said members 11 and 12 are prevented from passing beyond a center when the member M is extended. The lug 18 is preferably received within a recess 19 provided in an adjacent portion of the member 12.

The opposite side portions of the board 1 of the chest pad B has disposed thereacross and secured thereto the angle bars 20 having the depending flanges thereof provided with extensions 21 freely engaged with the member 6. The rear end portions of the angle bars 20 are continued by the bars 21^a of material length and disposed on a predetermined obtuse angle with respect to the bars 20. The outer or free end portion of each of the bars 21^a has pivotally engaged therewith as at 22, a leg section 23 preferably comprising an angle bar, said pivotal connection 22 comprising a transverse rod common to both sets of bars 21^a and legs 23. One end portion of the rod 22 is provided with a head a contacting with a leg 23 from without while the opposite end portion of the rod 22 has in threaded engagement therewith a wing nut 24 or the like. By proper manipulation of the nut 24 the joints between the bars 21^a and legs 23 may be loosened to effect the relative swinging adjustment or tightened to maintain said bars 21^a and legs 23 in desired relative relation.

Associated with each of the legs 23 and slidable with relation thereto is a foot 25 provided in its upper portion with a longitudinally disposed slot 26 through which the rod 22 is also disposed whereby the rod 22 also serves to provide means for holding the foot 25 in desired longitudinal adjustment with respect to the leg 23. The leg 23 at its longitudinal marginal portion is provided with the flanges 27 for contact with the foot 25 to hold said foot 25 against swinging movement with respect to the leg 23. The lower portion of the foot 25 is provided partially therewithal with a strengthening or reinforcing flange 28 and at its lower end carries a lateral extension 29 to which is adapted to be applied a pad 30 of rubber or kindred material.

Secured to the opposite side portions of the base board 1 of the abdominal support A are the angle bars 31 the forward end portions of said bars being downwardly offset, as at 32, and continued by the extension bars 33. The bars 33 are disposed on a

slight angular relation with respect to the bars 31 proper and the free extremity of each of said extension bars 33 is pivotally connected, as at 34, with a bar 20 and at a point 5 in relatively close proximity to the end of said bar whereby the pad A is supported for swinging movement in a vertical direction.

The bars 21 at a predetermined point inwardly of their outer ends are provided with 10 the ears or plates 35 which rotatably support and have disposed therethrough the opposite end portions of the intermediate member 36 comprised in the substantially U-shaped frame S the central portion of which being 15 provided with an offset portion 37. The side arms 38 of the frame S have their free ends freely and slidably engageable from below with the rear portion of the base board 1 of the abdominal pad A so that upon requisite 20 rocking movement of the frame S the rear portion of the pad A may be raised or lowered in accordance with the requirements of practice and which manipulation of the frame S is readily accomplished through the 25 medium of the offset portion 37 which serves as a hand grasp. The rear swinging movement of the frame S is limited by contact of the side arms 38 with the stop members 39 herein disclosed as suitably secured to the 30 bars 31.

A leaf spring 40 of substantially a semi-elliptical type has one end portion freely engaged, as at 41, with the member 6, said spring 40 when the device is extended for 35 use underlying the chest pad B and partially underlying the abdominal pad A with the opposite end portion of the spring freely in contact with the base board 1 of the pad A or more particularly a wear plate 42 suitably 40 secured to said board 1.

The rear portion of the chest pad B has arranged therebelow and disposed transversely thereof a rigid member or strap 43 suitably secured to the base board 1 of said 45 pad and to the bars 20 with the central portion of said member or strap offset to provide a substantially U-shaped loop or bracket 44 through which the spring 40 is directed.

50 Disposed through the intermediate portion of the loop or bracket 44 is a screw 45 adapted to engage the spring 40 from below in a manner whereby the tension of such spring 40 may be varied or regulated as required or entirely released. The free end portion 45' of the screw 45 has its periphery smooth and unobstructed in order to facilitate the raising of said screw for contact with the spring 40.

60 Interposed between and connecting the lower portions of the legs 7 is a cross bar 46 to maintain said legs in desired assembled relation.

65 Also associated with each of the legs 7 is a brace C comprising two members 47 and

48, the member 47 having one end portion pivotally connected, as at 49, to a bar 21 at a point spaced from but in relatively close proximity at the junction between said bar 21 and bar 20. The opposite end portion of the member 47 is pivotally connected, as at 50, with an end portion of the member 48, the opposite or outer end portion of said member 48 being pivotally connected, as at 51, with a collar 52 suitably positioned upon a leg 7. The pivoted end portion of the member 47 is provided with an extension 53 which overlies the adjacent portion of the member 48 when said members 47 and 48 are extended into working position 70 and said extension 53 is provided at one marginal portion with a laterally disposed lug 54 for coaction with the adjacent marginal portion of the member 48 to prevent said members 47 and 48 passing beyond center or alignment when the brace C is extended for use. The lug 54 is preferably received within a recess 55 provided in the adjacent marginal portion of the member 48. 80

The construction of my improved table 90 is such as to permit the same to be readily folded or compacted, when not in use, to facilitate its transportation from one place to another as into the home or other location whereby a patient may be treated without the necessity of attendants at the office of the chiropractor. 95

The folding of the table is particularly illustrated in Figure 13 of the accompanying drawings wherein it will be noted that the legs 7 are folded to underlie the chest pad B and the abdominal pad A and the head pad H is folded inwardly to underlie said pads B and A. The frame S is swung in a direction to closely approach the pad 105 A while each of the legs 23 and the foot 25 carried thereby is folded into close position with respect to the pad A. With this adjustment the rod 22 may be conveniently employed as a hand grasp whereby the device when folded may be readily carried. The structure of the table is of relative light weight, such weight preferably not exceeding twenty pounds. 110

In Figures 2, 6 and 9, the table is shown 115 in requisite adjustment for full support upon a floor and wherein the pads 30 are directly in contact with the floor, said pads 30 together with the pads 9 serving effectively to prevent slipping. 120

In Figure 3 is illustrated an adjustment of the various parts of my improved table whereby the same may be supported by a bed or the like and in which instance the legs 23 are upwardly disposed so that the 125 feet 25 may engage the side rail of the bed. By this arrangement the bedridden patient may be readily and conveniently positioned upon the table for desired treatment and in a manner whereby the lower portion of 130

the body and limbs may be kept covered. The bed takes the place of the back half of the office bench generally employed and in positioning the patient upon the table very little assistance is needed in turning the patient in bed or in placing the patient upon the table or in returning such patient to the bed for adjustment. When the table is employed as illustrated in Figure 3 the frame 10 S will be adjusted to release the abdominal pad upon the spring 40 to permit the same work to be done as on an office table in adjusting the lower part of the spine. It is to be understood that instead of a bed the 15 table may be adjusted to be supported in substantially the same manner by a chair or other article or furniture or the like but as this is believed to be an obvious arrangement it is thought that illustration of this 20 adjustment is unnecessary.

In Figure 4, the table is illustrated as adjusted for position for a treatment under "the new posture" method and wherein the head pad H is in lowered position so that 25 the patient may kneel upon a properly positioned pad P or the like and permit the body to be supported by the pads B and A. When so used, the pad A serves as a head support.

It will also be obvious that the table can 30 be adjusted otherwise than disclosed in the accompanying drawings as the requirements of practice may necessitate.

One of the bars 31 is provided at predetermined points spaced longitudinally thereof with the outstanding eye members 56 with which is adapted to be engaged a hand grasp 57 of any desired type. By this means the 35 device when folded may be carried with its longer dimension horizontally disposed and which is of a special advantage when being transported by a person of comparatively small stature.

When the device is employed in the manner as illustrated in Figure 3 and it is sometimes desired to vary the spacing of the pad A with respect to the bed or kindred support this adjustment is effected by maintaining each of the feet 25 at a required angle 45 with respect to the adjacent extension 21 of a bar 20 as illustrated in Figure 14. The foot 25 is maintained in desired adjustment through the medium of the slide 58 angular in cross section to overlie both flanges of the extension 21. The side flange of the slide is provided with a longitudinally disposed slot 59 through which is disposed a bolt 60 also directed through the adjacent flange of the extension 21 and engaged with the bolt 60 50 is a wing nut 61 whereby the slide 58 is effectively locked in desired position. The outer end of the slide is provided with a notch 62 which receives the portion of the foot 25 adjacent to the slide 58 and above 55 the rod 22 thereby limiting the inward

swinging movement of the upper portion of the foot 25 relative to the extension 21. This particular adjustment also provides for slight variations in elevation of the pads A and B.

In the embodiment of my invention as illustrated in Figures 17, 18 and 19 the cross strips 4' are connected to the angle bars 3' and the base boards 1' of the head supporting pads H' are provided with the loops 63 70 through which the strips 4' are freely disposed. This particular structure provides means whereby the pads H' may be adjusted one with respect to the other and in a manner whereby said pads may be arranged in close contact one with the other to eliminate the spacing therebetween.

The depending flange of each of the bars 3' is provided therealong with the spaced notches or recesses 64, 65 and 66, in which is adapted to be selectively engaged a cross rod 67 secured at its extremities to the brace members 68, each of said brace members 68 being pivotally engaged, as at 69 with a leg 7'. The notches 64 provide means whereby when the rod 67 is engaged therein it maintains the pads H' in a downward inclination, while the notch 66 maintains said pad inclined upwardly. The slot 65 as herein disclosed, is of a bayonet type and the rod 68 when engaged therein serves to maintain said pads substantially horizontal. The formation of this slot also serves to keep the rod 68 in place when the front end of the device is lifted from the floor as when adjusting the length of the front legs or when the table is being engaged with the bed or kindred support.

The pads H' together with the bars 3' are adapted to be completely separated from the remainder of the structure and particularly to permit said pads H' to be used as kneeling pads when the table is being employed in connection with "the new posture" method. For this reason the depending flange of each of the bars 3' is provided at its inner end with an open slot 70 which is adapted to freely engage the cross member 6'. To maintain the bars 3' in proper engagement with the cross member 6' I provide a yoke 71 freely engaged with the member 6' at opposite sides of the connection 41' of the spring 40'. The yoke 71 is adapted to straddle a pin 72 depending from the inner cross strip 4' and a bolt 73 is threaded through the outer end of the yoke 71 for contact with the pin 72 to maintain the bars 3' in requisite engagement with the cross member 6'. 115

When it is desired to remove the pads H' it is only necessary to screw the bolt 73 outwardly sufficient to permit the yoke 71 to drop whereupon the bars 3' and the pads H' operatively engaged therewith may be readily displaced.

From the foregoing description it is 130

thought to be obvious that a chiropractic table constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

15 I claim:—

1. A chiropractic table comprising a supporting structure, head pads hingedly engaged therewith, means for maintaining said pads in raised position, bars hingedly connected to the supporting structure, a chest pad mounted upon said bars, said bars extending on an incline rearwardly of said chest pad, supporting legs associated with the inclined portions of the bars, means for pivotally connecting said legs to said extended portions of the bars and holding said legs against movement with respect thereto, additional bars pivotally connected with the first named bars, an abdominal pad mounted on said last named bars, and means carried by the extended portions of the first named bars for supporting the abdominal pad.

2. A chiropractic table comprising a supporting structure, head pads hingedly engaged therewith, means for maintaining said pads in raised position, bars hingedly connected to the supporting structure, a chest pad mounted upon said bars, said bars extending on an incline rearwardly of said chest pad, supporting legs associated with the inclined portions of the bars, means for pivotally connecting said legs to said extended portions of the bars and holding said legs against movement with respect thereto, additional bars pivotally connected with the first named bars, an abdominal pad mounted on said last named bars, and a swinging frame carried by the extended portions of the first named bars for coaction with the abdominal pad to support the same.

3. A chiropractic table comprising a supporting structure, head pads hingedly engaged therewith, means for maintaining said pads in raised position, bars hingedly connected to the supporting structure, a chest pad mounted upon said bars, said bars extending on an incline rearwardly of said chest pad, supporting legs associated with the inclined portions of the bars, means for pivotally connecting said legs to said extended portions of the bars and holding said legs against movement with respect thereto, additional bars pivotally connected with the first named bars, an abdominal pad mounted on said last named bars, a swinging

frame carried by the extended portions of the first named bars for coaction with the abdominal pad to support the same, and means carried by the pad and coacting with the frame for limiting swinging movement of the frame in one direction.

4. A chiropractic table comprising a supporting structure, head pads hingedly engaged therewith, means for maintaining said pads in raised position, bars hingedly connected to the supporting structure, a chest pad mounted upon said bars, said bars extending on an incline rearwardly of said chest pad, supporting legs associated with the inclined portions of the bars, means for pivotally connecting said legs to said extended portions of the bars and holding said legs against movement with respect thereto, and a foot coacting with each of the supporting legs, said foot being provided with a lateral extension.

5. A chiropractic table comprising a supporting structure, head pads hingedly engaged therewith, means for maintaining said pads in raised position, bars hingedly connected to the supporting structure, a chest pad mounted upon said bars, said bars extending on an incline rearwardly of said chest pad, supporting legs associated with the inclined portions of the bars, means for pivotally connecting said legs to said extended portions of the bars and holding said legs against movement with respect thereto, additional bars pivotally connected with the first named bars, an abdominal pad mounted on said last named bars, means carried by the extended portions of the first named bars for supporting the abdominal pad, and a spring operatively engaged with the supporting structure for contact from below with the abdominal pad.

6. A chiropractic table comprising a supporting structure, head pads hingedly engaged therewith, means for maintaining said pads in raised position, bars hingedly connected to the supporting structure, a chest pad mounted upon said bars, said bars extending on an incline rearwardly of said chest pad, supporting legs associated with the inclined portions of the bars, means for pivotally connecting said legs to said extended portions of the bars and holding said legs against movement with respect thereto, additional bars pivotally connected with the first named bars, an abdominal pad mounted on said last named bars, means carried by the extended portions of the first named bars for supporting the abdominal pad, a spring operatively engaged with the supporting structure for contact from below with the abdominal pad, and means for varying the tension of said spring.

7. A chiropractic table comprising a supporting structure comprising a cross member, connected bars, the extremities of the

bars having open slots engageable with the cross member of the supporting structure, a yoke hingedly connected with the cross member of the supporting structure, a member depending from the connected bars adapted to be straddled by the yoke, and a member adjustable through the yoke and con-

tacting with the depending member to hold the bars against displacement with respect to the supporting structure.

10 In testimony whereof I hereunto affix my signature.

ROBERT H. HARRIS.
